UNITED STATES PATENT OFFICE

BENZION WOLF, OF CHICAGO, ILLINOIS

GARTER

Application filed January 22, 1930. Serial No. 422,501.

This invention relates in general to garters and particularly to anatomic garters of a type similar to that disclosed in Patent No. 1,737,067, issued November 26, 1929.

5 The object of the present invention is to provide an anatomic garter of new and novel design.

Another object is to provide a garter of the class described whereby the vertical 10 member or strip is made extensible to conform to various lengths of socks.

Another object is to provide new and novel means for supporting the band or anklet portion of the garter about the ankle of the 15 wearer.

A further object is to provide improved means for inserting stays in the vertical extension or strip of the garter.

A still further object is to provide improved 20 means for fastening the band or anklet in position about the ankle of the wearer.

Numerous other objects and advantages 25 will be apparent throughout the progress of the following specification.

The invention comprises in general a garter having a band or lower anklet portion which is adapted to fit around the ankle of the wearer and support the garter clasp and 30 the vertical extension of the garter. The vertical extension member or strip which is preferably tape, is provided to accommodate stays of various lengths to conform with the extensibility of the vertical member or strip.

35 The strip may be attached to a clasp and is made extensible or contractable to conform with socks of different lengths. The clasp may be attached to the vertical strip or it may be a separate unit entirely as shown in

40 the various modifications in the drawings. The anklet portion or band may be of any type desired, being provided with a buckle through which the strip extends, although it is preferable that it be made of the spiral- 45 ing type so as to prevent bunching and overlapping. Various means may be provided for fastening the band or anklet in position.

The accompanying drawings illustrate a 50 selected embodiment of the invention and the views therein are as follows:

Fig. 1 is an elevation showing the improved garter in position on the leg of a wearer and supporting a sock.

Fig. 2 is a detail elevation of one form of the improved garter. 55

Fig. 3 is a detail, sectional view showing the garter fastened to a sock and arranged in non-extensible position.

Fig. 4 is a detail front view of the device shown in Fig. 3. 60

Fig. 5 is a detail sectional view showing the garter in extended position.

Fig. 6 is a detail elevation of the device shown in Fig. 5. 65

Fig. 7 is a detail perspective view showing the manner in which reinforcing stays may be inserted into the vertical member or strip.

Fig. 8 is a detail sectional view on the line 8—8 of Fig. 7. 70

Fig. 9 is a view showing a modified form of garter in position on the leg of a wearer.

Fig. 10 is a detail, perspective view of the improved garter showing modified means for attaching the anklet or band together. 75

Fig. 11 is a detail, vertical, sectional view showing the clasp detached from the strip or vertical member.

Fig. 12 is a detail perspective view of the band or anklet portion of the garter shown 80 in Fig. 9.

Referring to the drawings, 1 designates a band or anklet portion which is adapted to fit around the ankle of the wearer to which a vertical member or strip 2 is fastened in any 85 convenient manner such as by stitching 3. This band or anklet portion may be made of any kind of material desired, elastic or otherwise, although it is preferably made of a non-elastic material such as ordinary tape or webbing. The extensible member or strip 2 can also be made of any fabric whatever, although it is preferably made of the same kind of material as the band is made. The strip 2 is preferably made of two plies of fabric 4 and 5 which are fastened together by means of stitching 6. The fabric 5 is preferably broken off or cut away at the points 7, 7, Fig. 7, to provide a lower portion 8 and an upper portion 9. The portion 9 is prefer- 100

ably provided with a flap or tongue 10 which is stitched to the upper fabric 9 at 11. The strip 2 is open at the top as indicated at 12 in order to receive a reinforcing member or stay 13. The fabric portion 4 extends beyond the top of the fabric 5 to provide extensibility of the strip and may carry a clasp 14, Figs. 1 and 3. This clasp is adapted to cooperate with a slidable keeper 15, the keeper having an upstanding knob 16 about which the clasp 14 cooperates for fixedly securing a sock 17 to the slidable keeper 15. The clasp and the keeper with its attached knob 16 can be of the conventional design employed in garters of other types than the present.

The slidable keeper 15 is adapted to be moved longitudinally of the strip 2 and may be slidably mounted relative to the entire strip 2 comprising the fabrics 4 and 5 or to the fabric 4 alone. The purpose of this slidable keeper is to make the garter conformable with socks of various lengths. Where the sock is relatively short, the strip 2 may be pulled or looped through the slidable keeper to provide a festoon 18 as clearly shown in Fig. 3. In this latter embodiment the stay 13 may be relatively short and inserted between the two plies of fabric 4 and 5, Fig. 3. The stay may be substantially rigid and at the same time have certain qualities of flexibility such as a steel or bone corset stay. If a substantially flexible stay is provided, the stay may be inserted in the pocket between the two fabrics 4 and 5 at 20, Fig. 7, and then slid downwardly into position. Instead of sliding the stay from the top, it may be first slid in the pocket below the flap 10 and then kinked or bent and inserted upwardly in the pocket above the flap 10.

If, however, the improved garter is to be applied to a longer sock, the strip 2 is pulled through the slidable keeper 15 until the desired length is obtained. In Fig. 5 the festoon is practically taken up and the slidable keeper is almost extended to its limit. The stay 13 is considerably lengthened to form a support for the garter to conform with the longer sock.

It is to be noted that the strip 2 which includes either the fabric 4 or both the fabrics 4 and 5, first extends downwardly through the upper slot 21 in the slidable keeper and then passes around the bottom of the keeper, then through the lower slot 22 of the keeper and finally through the first slot 21, the portion 23 extending above the slidable keeper providing a flap to which the clasp 14 is attached.

Instead of having the clasp 14 fastened to the strip 2, it may be detached as shown in Fig. 11, and applied about the knob or button 16 of the slidable keeper 15.

65 While the band or anklet 1 shown in Figs.

1 and 2, may be used, it is preferable that all bunchiness, as far as practicable, be eliminated and the construction adopted as shown in Figs. 9, 10 and 12.

In these latter figures the preferred form of band or anklet member 30 comprises an ordinary piece of fabric material such as that previously described relative to Figs. 1 and 2, but instead of being overlapped, the edges are separated in spiral form as clearly shown in Figs. 9, 10 and 12. The overlapping of the band shown in Figs. 1 and 2 may be undesirable for the reason that the material overlaps causing a bunchiness and is inconvenient and uncomfortable, particularly in hot weather.

The band or anklet 30 is fastened to the strip 2 in any convenient manner such as by the usual stitchings 3 and is arranged about the ankle of the wearer in substantially spiral form so that one end 31 is arranged above the other end 32 in the manner clearly shown in Figs. 9 and 12. The bottom edge 33 of the end 31 is preferably arranged adjacent to and almost abutting the upper edge 34 of the end 32. This band or anklet may also be provided with a slidable keeper 35 whereby the band or anklet may be extended or contracted to conform with the size of the wearer's ankle. It is also preferable that the two ends 31 and 32 be fastened together in any convenient manner and this may be accomplished by providing an eye 36 on the upper end which engages a hook 37 provided on the slidable keeper 35, Fig. 12.

Instead of employing a keeper and hook, a plurality of eyes 40, Fig. 10, may be secured to either one of the ends, being shown on the lower end 32, Fig. 10. These eyes are adapted to fit over and engage a knob or button 41 provided on any suitable member 42 which may be secured to the end 31 of the band in any convenient manner such as by stitching 43.

By employing the spiraled or coiled form of band, all bunching is eliminated and the parts fit snugly about the ankle without causing any pressure against the blood streams. This spiraling or coiling characteristic of the band causes the material to lie perfectly flat against the wearer's leg, is relatively thin and eliminates all undue thickness.

In Fig. 11 the slidable keeper 15 may be slipped from the loose end 50 of the strip 4 and moved along the strip to any position desired. In this embodiment the reinforcing member 13 may be inserted in the opening 51 between the fabrics 4 and 5 in the strip 2, or it may be inserted in the manner shown in Figs. 7 and 8.

The invention comprises an anatomic garter which is capable of adjustment for fitting socks of various lengths and permits stays to be inserted in the strip or vertical portion of the garter to conform with the

various extensions of the garter. The band or anklet construction of the preferred type eliminates all bunchiness and presents a flat surface to the ankle of the wearer. An anatomic garter of the present type overcomes binding of the blood streams, a condition which is prevalent in the conventional garters which fit between the knee and the calf of the wearer. The present garter presents numerous advantages over the conventional type of garters, permits adjustment both vertically and about the ankle, and can be readily and economically manufactured.

Various changes may be made in the form, construction, and arrangement of the parts without departing from the spirit of the invention or sacrificing any of the advantages thereof, and the right is hereby reserved to make all such changes which fairly fall within the scope of the following claims.

Having thus described my invention, what I claim as new and desire to secure by Letters Patent is:

1. A garter comprising an ankle band, a strip extending upwardly therefrom, a stay for reinforcing said strip, a slideable keeper engaging the strip for effecting adjustment thereof, and a clasp cooperating with the keeper for fastening the garter to a sock.
2. A garter comprising a spiraled or coiled ankle band spirally encircling the ankle of a wearer, means arranged at the upper edge of said band near one end thereof and engaging means on the lower edge of the band near the other end of said band to hold the band in position and to permit the band to be adjusted to accommodate ankles of different size, a vertical member fastened to said band, means for lengthening or shortening the vertical member to accommodate socks of different length, means for fastening a sock to said vertical member, reinforcing means for said vertical member, and means for permitting the reinforcing means to be inserted into the vertical member at a plurality of positions.

In witness whereof, I have hereunto subscribed my name.

BENZION WOLF.
